Application September 19, 1942, Serial No. 458,990

13 Claims. (Cl. 226—82.4)

1

This invention relates to container sealing machines and more particularly to mechanism for seaming containers or cans of square or rectangular cross section and to control mechanism for inter-relating and timing the operation of the seaming mechanism and parts for positioning and otherwise preparing a container for being sealed. The invention may be embodied especially in machines in which a pad or supporting element is arranged to move a container and container end relatively toward a chuck and after chucking to bring seaming rolls into operation. The container may be vacuumized before the seaming operation is performed, and the cans may be held stationary during the seaming operation.

An object of the invention is to provide a machine of the character stated with novel and improved operating mechanisms and interlocking controls for insuring that the proper steps for conditioning the container and its contents for sealing will be performed before the container is sealed.

Another object of the invention is to provide an improved fluid pressure operated mechanism for moving a container first into vacuumizing position and then to chucked position in readiness for being sealed.

Another object of the invention is to provide fluid pressure operated mechanism for first moving a container and a container end relatively toward but not all the way to chucked position, and other fluid pressure operated mechanism responsive to vacuumizing of the container for then automatically continuing the relative movement to place the container and container end in chucked position.

Another object of the invention is to provide a container sealing machine in which vacuumizing of a sealing chamber is effected automatically in response to closing of a door on the sealing chamber.

Another object of the invention is to provide a container sealing machine in which a fluid pressure motor for moving a container and container end toward chucked position is operable under the control of a solenoid in turn controlled by or being responsive to closing of the sealing chamber door.

Another object of the invention is to provide a machine of the class referred to in which mechanism for moving a container and container end to chucked position is controlled automatically by a device responsive to fluid pressure in the sealing chamber.

Another object of the invention is to provide 55 a one-revolution pilot clutch shown in section;

2 a machine of the character stated in which two fluid pressure motors are provided for moving a container toward and then all the way to chucked position, one of the motors being operable only after the container and end have been moved toward but then stopped short of chucked position.

Another object of the invention is to provide electrically controlled means for effecting operation of the seaming mechanism only after a container and end have been chucked.

Another object of the invention is to provide a machine of the character referred to including a continuously rotatable seaming head carrying seaming rolls normally held out of seaming position by springs which are yieldable to permit movement of the seaming rolls into seaming position after a container and end have been chucked.

Another object of the invention is to provide a 20 machine of the character stated including a continuously rotatable seaming head, seaming rolls carried thereon, and differential gearing controllable in a novel manner for moving the seaming rolls into seaming position.

Another object of the invention is to provide a 25 machine of the character stated in which movement of the seaming rolls into seaming position is brought about by engagement of a driving clutch, the engaging of which is effected by operation of a pilot clutch device adapted when engaged to operate for a predetermined period and then stop.

Another object of the invention is to provide 30 a simple and effective means for centering or aligning a container with a chuck.

A further object of the invention is to provide 35 a simple and effective spring urged knock out device for ejecting or forcibly removing seamed containers from a chuck.

Other objects of the invention will become 40 apparent from a reading of the following detailed description, the appended claims, and the accompanying drawings.

In the drawings:

45 Figure 1 is a diagram showing the general interrelation of vacuum or fluid pressure and electrical control means with other parts including a sealing chamber, and lifting and chucking cylinders;

Figure 17 is a fragmentary horizontal section showing container holders mounted within the sealing chamber and carried respectively by the sealing chamber rear wall and the sealing chamber door; and

Figure 18 is a fragmentary vertical section showing the container holders illustrated in Figure 17.

The operational relationship of the parts will first be described with reference to the diagrammatic showing in Figure 1, it being thought that with the general inter-relation of the parts and sequence of operations once well in mind the detailed description of an illustrative structural embodiment will be more easily followed.

Parts referred to in the description of Figure 1 but not shown therein are illustrated in other figures to be described in detail later.

Referring to Figure 1, a sealing chamber or bell indicated at A encloses seaming mechanism including a chuck for holding a can end in position on top of a can body to be seamed thereto. Mounted to reciprocate in the cylinder B of a fluid pressure operable motor is a piston connected to and adapted to move a can pad or support mounted in the chamber A to position a supported can body in vacuumizing position with its top spaced a predetermined distance below the chuck. A piston reciprocable in the cylinder C of another fluid pressure operable motor is arranged to move the can to chucked position after lifting of the can to vacuumizing position and after the chamber A has been vacuumized.

Chucking of the can automatically effects engaging of a clutch which brings the seaming mechanism into operation for a predetermined period, the clutch being then automatically disengaged and the parts returned to their starting positions.

As indicated in Figure 1 a vacuum pump D communicates through a conduit 1 with a valve 2 in turn communicating with the chamber A by means of a conduit 3. The valve 2 is provided at 4 with an outlet to the atmosphere. Actuation of the valve is controlled by a solenoid 5 operatively connected to the valve at 6 and being connected across an electric power supply line 7 by means of conductors 8 and 9, the latter having interposed in it a switch 10. The switch 10 is normally open and is adapted to be closed only momentarily when the sealing chamber door is closed. Momentary energizing of the solenoid 5 operates the member 6 to permit the valve 2 to be operated to place the conduit 1 in communication with the sealing chamber A. Although the switch 10 is closed only momentarily in response to movement of the door to closed position, the valve 2 will remain in its operated position until it is reset by rotation of a resetting arm 11 engageable with a follower 12 projecting from the valve 2. Arm 11 is normally at rest but is brought into operation when a can is brought into chucked position and is timed so as to reset the valve and place chamber A in communication with the outlet 4 to the atmosphere as soon as seaming operation has been performed.

To enable operation of the piston within the lifting cylinder B a conduit 13 provides communication between the vacuum pump D and a valve 14 having an atmospheric outlet 15 and being arranged to communicate through conduits 16 and 17 respectively with opposite ends of the cylinder B. Before the can pad is lifted the conduit 13 is in communication with the conduit 17, the conduit 16 is connected to the outlet 15, and the piston in the cylinder B and the can are in retracted positions. Closing of the sealing chamber door automatically closes a switch 18 to complete a circuit through conductors 19 and 20 and a solenoid 21, resultant operation of which actuates the valve 14 through a connecting member 22 to place the vacuum conduit 13 in communication with the conduit 16 and, simultaneously, to place the atmospheric connection 15 in communication with the conduit 17. The piston in the cylinder B will then move the can to vacuumizing position, it being understood however that this operation does not move the can to completely chucked position.

The cylinder C, within which is mounted the piston which effects movement of the can to chucked position, communicates at its opposite ends respectively with conduits 23 and 24 which lead to a valve 25 open to the atmosphere at 26 and leading through a conduit 27 to the vacuum pump D. Normally the valve 25 provides communication between the conduits 27 and 23 and between the conduit 24 and the atmospheric connection 26. A solenoid 28 connected to the valve 25 by an operating member 29 is connected across the line 7 by a conductor 30 and a conductor 31 interposed in which is a normally open switch 32. The switch 32 is adapted to be closed by contraction of a Sylphon bellows 33 which is in constant communication through a conduit 34 with the sealing chamber A. The arrangement is such that when the desired predetermined degree of vacuum has been produced in the chamber A the bellows 33 closes the switch

32 thereby energizing the solenoid 28 and operating the valve 25 to place the vacuum line 27 in communication with the conduit 24, causing the piston in the cylinder C to move the can to chucked position in readiness for being sealed.

Movement of the can to completely chucked position automatically brings about operation of seaming mechanism to be described hereinafter. Generally stated, the seaming mechanism may be similar to that shown in the patent to Kronquest 2,271,152, granted January 27, 1942. Operation of the seaming mechanism is initiated by rocking of a clutch release shaft indicated at 35 in Figure 1 under the action of a solenoid 36 having an operating member 37 connected to the shaft 35 by an arm 38 fast with the shaft. The solenoid 36 is connected across the line 7 by conductors 39 and 40, the latter having interposed therein a normally closed switch 41 and a normally open switch 42.

When the piston in the cylinder C moves the can to chucked position it operates a lever 43 which then engages and closes the switch 42, thereby energizing the solenoid 36 to effect rocking of the shaft 35 to in turn effect engagement of a one-revolution pilot clutch and operation of the seaming mechanism controlled thereby. As soon as the one-revolution clutch is engaged and begins to drive, it actuates an interrupter arm 44 which opens the switch 41 to de-energize the solenoid 36. However, de-energizing of the solenoid 36 will not immediately disengage the pilot clutch and the latter will drive through a complete revolution.

After the seaming operation has been performed, the resetting arm 11, which is moved in timed relation to the seaming mechanism, will engage the follower 12 and operate the valve 2 to place the chamber A in communication with the atmosphere at 4, thereby relieving the vacuum in the chamber A and permitting the Sylphon bellows 33 to expand and open the switch 32. This will de-energize the solenoid 28 and operate the valve 25 to place the conduit 24 in communication with the atmosphere at 26, thereby retracting the piston in the cylinder C to unchuck the can, and to rock the lever 43 and open the switch 42. This will take place before the pilot clutch has completed its one-revolution driving. Thus, when the one-revolution clutch has completed a single revolution the switch 42 will be open, the solenoid 36 will be de-energized, and the clutch will become disengaged and cannot be re-engaged until a new and complete cycle is performed.

When the sealing chamber door is opened, the switch 18 will open, whereby the solenoid 21 will be deenergized, the valve 14 will place the conduit 16 in communication with the atmosphere, and the pad and can thereon will be moved away from the chuck.

The illustrative structural embodiment of the invention shown in Figures 2 to 18 comprises a combined casing and frame E which supports the bell or sealing chamber A, the pad lifting cylinder B, the chucking cylinder C, and seaming mechanism generally designated F driven by a motor G.

The sealing chamber A is formed with an access opening adapted to be closed by a door 45 provided with a gasket 46 engageable with the marginal walls of the opening for maintaining a vacuum seal when the door is closed. The bottom wall 47 of the chamber A is apertured to receive a bearing 48 for reciprocally mounting

can positioning means comprising a lifting rod member 49. The rod 49 is bored inwardly from its upper end to receive a stem 50 having threaded engagement with the rod 49 to permit vertical adjustment of the stem 50 with respect to the rod. A lock nut 51 is provided for holding the stem 50 in vertically adjusted position. A can support or pad element 52 is keyed as at 53 to the upper end of the stem 50. The rod 49 has a flat side 49a in sliding engagement with a block 54 for preventing rotation of the rod 49 and pad element 52.

The rod 49 extends downwardly beyond the bearing 48, into the lifting cylinder B, and thence freely through a sleeve 56 fast with and extending downwardly from a piston 57 mounted to reciprocate in the cylinder B. The lower end of the rod 49 is threaded to receive a nut 58 which abuts against the bottom of a strap 56a secured to the lower end of the sleeve 56. A spring 59 is interposed between the top of the piston 57 and a flange 60 on the rod 49. It will be apparent that when the piston 57 is raised, the spring 59 will transmit lifting force to the flange 60 and hence to the rod 49 for lifting the pad 52. Air tight packing 61 is interposed between the piston 57 and the rod 49.

The seaming mechanism F includes a chuck element 62 disposed centrally over the rod 49 and seaming rolls 63 (see Figures 6 and 9). The chuck is non-rotatable and serves to hold a can and can end against rotation when the can end is pressed up against the bottom of the chuck. Means are provided for centering and lining up the can with respect to the chuck. To this end the bell A and door 45 are provided with means for embracing a can carried by the pad 52. As shown in Figures 2, 17 and 18, can holders 64 and 65 are carried respectively by the bell A and the door 45 adjacent the bottom of the bell. The holder 64 is generally of a U shape and includes a flange 66 secured by screws 67 to the rear wall of the bell. Preferably the bell is provided with a vertically extending series of attaching stations comprising tapped holes 68, selected ones of which may receive the screws 67 for adjusting the height of the holder 64 in accordance with the size of the can to be sealed. The holder 64 includes a rear part 69 and legs or sides 70 and 71, the latter of which is bifurcated horizontally as shown in Figure 18.

The complementary door-mounted holder 65 includes a flange 72 adapted to be secured by screws 73 engageable selectively in vertically spaced attaching station tapped holes 74. The holder 65 includes a single side leg 75 which is adapted, when the door is closed, to fit in between the upper and lower portions of the bifurcated leg 71 of the holder 64.

Similar holders 64a and 65a mounted on the bell and door respectively at the top of the bell are formed respectively with vertical extensions 64b and 65b for embracing the upper end of a can body and a can end positioned in readiness for chucking and then sealing.

In operation, when a can body and superposed can end are placed on the pad 52 and the door 45 is closed, the holders 64, 65, 64a and 65a will center or align the can body and can end with respect to the pad 52 and chuck 62.

As previously explained, closing of the door 45 momentarily closes the switch 10, thereby operating the solenoid 5 and the valve 2 so as to vacuumize the sealing chamber A. As shown in Figure 10 the valve 2 comprises a body 76 and a

reciprocable "D" valve element 77 urged by a spring 78 to a position providing communication between the conduit 1 leading to the vacuum pump and the conduit 3 leading to the sealing chamber. A pad 79 on the valve element 77 is engageable with a stop 80 on the valve body 76 for limiting the throw of the valve element 77 under urge of the spring 78. A screw 81 is provided for adjusting the loading of the spring 78.

A latch 82 pivoted as at 83 on the valve body 76 normally engages the pad 79 for maintaining the valve element 77 in the non-vacuumizing position shown in Figure 10 wherein the sealing chamber communicates through the conduit 3 with the atmospheric outlet 4. For permitting the spring 78 to move the valve to vacuumizing position, the plunger 84 of the solenoid 5 is connected through the link member 6 to the latch 82. Thus when the solenoid 5 is energized momentarily, the latch 82 is lifted and the spring 78 will move the valve element 77 to place the sealing chamber in communication with the vacuum pump through the conduits 3 and 1. The valve element 77 will remain in this position until it is reset by actuation of the arm 11 previously referred to.

As shown in Figures 12 and 13, the switch 10, which is operable in response to closing of the door 45, includes an operating button 85 positioned to be moved by a lever 86 pivoted as at 87 on the bell casing A. The lever 86 is formed with a nose 88 adapted to be engaged by a pawl 89 pivoted as at 90 on the door 45. When the door is moved to closed position, the pawl 89, being held against clockwise movement as viewed in Figure 12 by contact with a stop pad 91 on the door, engages the nose 88 of the lever 86 and cams it to rock the lever 86 and push inwardly on the switch button 85. When the door moves to its completely closed position, the pawl 89 will proceed beyond the nose 88 of the lever 86, permitting the switch button 85 to return the lever 86 to its initial position. Thus the circuit through the solenoid 5 will be closed only momentarily while the pawl 89 is riding over the nose 88 during closing of the door.

When the door is opened the pawl 89 will engage the nose 88 and will rock freely in a counter-clockwise direction as viewed in Figure 12 so as to ride over the nose 88 without rocking the lever 86 and without closing the switch 10. Therefore, the solenoid 5 will not be energized when the arm 11 resets the valve element 77, and the latch 82 will be free to re-engage the pad 79 and hold the valve element 77 in its Figure 10 position until the door 45 again is moved from its open to its closed position to start a new cycle.

Closing of the sealing chamber door 45 closes the switch 18 and holds it closed to energize the solenoid 21 and operate the valve 14. As shown in Figure 11, the valve 14 includes a body 92 and movable "D" valve element 93 cooperable with the conduit 13 and with ports 94 and 95 communicating with conduits 16 and 17 respectively. The valve element 93 is hollow to enable the ports 94 and 95 to be placed in communication with the atmospheric outlet 15. The solenoid 21 has a plunger 96 connected to the valve element 93 by the link member 22.

In operation, when the valve chamber door 45 is closed, resultant closing of the switch 18 will energize the solenoid 21 so as to move the "D" valve element 93 to a position providing communication between the conduits 13 and 16 and between the conduit 17 and the atmospheric outlet 15. Thus the top of the lifting cylinder B

(above the piston 57) will be connected to the vacuum pump whereby the piston 57 will be raised and the rod 49 and pad 52 will be lifted.

When the piston 57 has been raised and prior to the operating of the chucking cylinder C, the can and can end supported on the pad 52 will be spaced a predetermined short distance below the chuck 62. Thus the can end will not be pressed against the can and the interior of the can can be vacuumized effectively.

After a predetermined degree of vacuum has been established within the sealing chamber A, the piston reciprocable in the cylinder C operates to lift the rod 49, pad 52 and supported can and can end further and into chucked position. As shown in Figure 14 a piston 97 mounted to reciprocate in the cylinder C is equipped with a rod 98 extending through a packing gland 99. To the outer end of the rod is pivoted as at 100 the end of a link 101, the other end of which is pivoted at 102 to one end of the lever 43 previously referred to and which is pivoted on the frame E as at 103. To the other end of the lever 43 is pivoted as at 104 to one end of a link 105, the other end of which is pivoted as at 106 to a cam lever 107 fulcrumed on the underside of lifting cylinder B as at 108. The lever 107 is formed with a cam slot having an upper stop surface 109 and a lower driving surface including a gradual rise portion 110, a steep rise portion 111, and a dwell portion 112. The cam slot receives a follower roller 113 carried at the lower end of the lifting rod 49. In the form shown, the roller is journaled on the strap 56a secured to the lower end of the sleeve 35 56.

Prior to establishing the desired degree of vacuum in the chamber A, the piston 97 and parts operated thereby will be in the position shown in Figures 2 and 14. The roller 113, having previously been raised when the piston 57 was raised, will be in engagement with the top or stop surface 109 of the cam groove. When the valve 25 is operated to place the conduit 24 in communication with the vacuum pump, the piston 97 will be moved to the left as viewed in Figure 14 thereby rocking the lever 43 clockwise as viewed in Figure 2 to pull the link 105 and rock the cam lever 107 counterclockwise. During the first part of the cam lever rocking, the roller 113 will be disposed above and out of contact with the bottom of the cam groove, engaging instead the top surface 109 of the groove. The cam top surface 109 is of such shape as to permit the roller 113, rod 49, piston 57 and pad 52 to move further upwardly under the action of the vacuum in the upper end of the cylinder B, thereby raising the can and can end further toward chucking position. Just before the cam lever 107 completes its rocking movement, the steep rise portion 111 of the bottom of the cam groove will engage the roller 113 and cam it forcibly upwards so that the piston 97 will exert a further lifting force on the rod 49 to move the can and can end to completely chucked position.

When the seaming operation has been completed and the valve 25 has been operated to place the conduit 23 in communication with the vacuum pump, the piston 97 will move back to the position shown in Figure 14, thereby rocking the cam lever 107 clockwise as viewed in Figure 2. The upper surface 109 of the cam lever groove will press downwardly on the roller 113 to forcibly lower the rod 49 and move the container supporting pad 52 downwardly.

Movement of the piston 97 is controlled by the

valve 28 operated by the solenoid 28 which is energized by closing the switch 32 in response to attainment of a predetermined degree of vacuum in the sealing chamber A. As shown in Figure 14, valve 28 includes a body 114 and a reciprocable "D" valve element 115 cooperable with ports 116 and 117 leading respectively to the conduits 24 and 23. The valve element 115 is hollow so as to enable the ports 116 and 117 to be placed respectively in communication with the atmospheric outlet 26.

The solenoid 28 is equipped with a plunger 118 connected through the member 29 to the valve element 115. As shown in Figure 1 and as previously explained, the switch 32 which controls the energizing of the cylinder 28 is normally open and is permitted to be closed by contraction of the Sylphon bellows element 33 connected through the tube 34 to the sealing chamber A.

As previously stated with reference to Figure 1, rocking of the arm 43 for moving the can and can end to chucked position closes the switch 42 for initiating operation of the seaming mechanism F. Preferably the switch 42 is operated by an adjustable tappet 119 carried by the lever 43 as shown in Figure 2.

Referring more particularly to the construction of the seaming mechanism, a stationary web 120 fast with the frame E has an upstanding flange surmounted by a cap 121 secured to the flange by screws 122. A nut 123 having threaded engagement with a sleeve 124 bears against the top of the cap 121 for drawing a shoulder 125 on the sleeve 124 up against the bottom of the cap 121.

An antifriction bearing 126 mounted on the sleeve 124 journals a seaming head 127. An aligning sleeve 128, secured to the seaming head 127, surrounds a bearing 129 mounted on the sleeve 124, thereby cooperating with the antifriction bearing 126 for preventing the seaming head from being canted.

A ring gear 130 secured to the head 127 meshes with a gear or pinion 131 fast with a shaft 132 coupled as at 133 to the shaft 134 of the electric motor G. Thus the seaming head 127 is continuously driven when the motor G is in operation.

The seaming head 127 is formed with four equidistantly spaced bearing sleeves 135 having bearing liners 136 secured respectively therein. Mounted to turn in each bearing liner 136 is a hub sleeve 137 provided with end flanges 138 and 139 cooperable with the ends of the associated liner 136 for preventing axial displacement of the sleeve 137. Levers 140 integral with the respective hub sleeves 137 are provided at their free ends with pins 141 on which rollers 142 are journaled. The rollers 142 are arranged to run in a slot or groove 143 formed in a cam member 143a carried at the lower end of the sleeve 124.

When the seaming head is rotated the cam 143a displaces the rollers 142 radially so as to rock the levers 140, causing the free ends of the levers to trace a path similar to but outside the margin of the can to be seamed. The seaming rolls 62 are journaled as at 63a on arms 144 pivoted as at 145 on the levers 140, the arrangement being similar to that disclosed in the Kronquest Patent 2,271,152, previously referred to. Normally, springs 146 respectively connected between each arm 144 and its associated lever 140 hold the seaming rolls 62 out of seaming position. Normally inactive means for rocking the arms 144 on the lever 140 to seaming position includes for

each arm 144 a spindle 148 rotatable within the sleeve hub 137 and carrying at its lower end a cam 149 secured to the spindle 148 by a cap 150. Each cam 149 is generally circular in contour except for a rise 151 cooperable with a follower nose 152 mounted on the end of the seaming roll arm 144 opposite the end thereof on which the seaming roll 62 is mounted.

In operation, and prior to the conditioning of the apparatus for performance of the seaming operation, the seaming head 127 will rotate constantly so as to carry the levers 140 and arms 144 orbitally about the chuck 62. The cam groove 143 will move the rollers 142 so as to rock the levers 140 and arms 144 about the axes of the sleeves 135 to cause the seaming rolls 62 to move around the outside of but slightly spaced from the chuck 62. At this time the follower noses 152 on the arms 144 will be in contact with the circular portions of the cams 149. When the container to be sealed has been vacuumized and chucked, the cams 149 will be rotated about their own axes to bring the rise portions 151 into engagement with the follower noses 152, thereby rocking the arms 144 about their respective pivots 145 and moving the seaming rolls 62 into seaming position. The cams 149 may be so formed and positioned relatively to each other as to move two of the seaming rolls into seaming position first so as to perform "first operation" seaming and so as then to move the other two seaming rolls into engagement with the cam to perform the "second operation" seaming.

The follower noses 152 may be mounted for adjustment about pivots 153 on the arms 144, adjustment being effected by turning screws 154 and 155.

Gears 156 secured respectively to the spindles 148 mesh with an interponent gear 157 which normally revolves freely with the head 127 but which can be moved relatively to the head 127. The gear 157 is carried on a larger gear 158 having a hub 159 journaled on a bearing 160 mounted on the aligning sleeve 128. It is desirable that the cams 149 normally be maintained with certainty in such positions that the rise portions 151 thereon will be displaced from and out of contact with the follower noses 152. For accomplishing this purpose springs 161 are interposed between pins 162 carried eccentrically on the respective gears 156 and anchoring pins 163 carried by the gear 130. When the gear 157 is free to turn, the springs 161 will contract so as to move each pin 162 into a straight line passing through the associated pin 163 and the axis of the associated spindle 148. The pins 162 are so located angularly with respect to the cams 149 that when the gears are positioned with the pins 162 aligned with the pins 163 and the axes of the spindles 148, the rise portions 151 of the cams 149 will be out of contact with the follower noses 152.

When the container has been conditioned for seaming, it is necessary to rotate the gear 157 relatively to the seaming head 127 so as to rotate the gears 156 and the cams 149 about their own axes and thereby move the cam rise portions 151 into engagement with the follower noses 152. The gear 158 is in mesh with a gear 164 journaled by a bearing 165 so as to rotate freely about the shaft 132. Normally there is no driving connection between the shaft 132 and the gear 164 and the gears 158 and 157 are free to rotate in unison with the head 127.

A driving clutch interposed between the shaft 75 132 and the gear 164 comprises a clutch member

166 secured to the gear 164 to rotate therewith and having jaw teeth 167, and a clutch member 168 splined as at 170 to slide on but rotate with the shaft 132 and having jaw teeth 169. The clutch member 168 is formed with a groove 171 which receives a pin 172 carried by a lever 173 fixed to a shaft 174 journaled to rock in a fixed bearing 175. Rocking of the shaft 174 will move the clutch member 168 downwardly so as to effect engagement of the clutch teeth 169 with the teeth 167 on the clutch member 166. Thereafter, the gear 164 will be driven directly from the shaft 132. Inasmuch as the gear ratio between the gears 131 and 130 driving the head 127 is different from the gear ratio between the gears 164 and 158, the gear 157, carried by the gear 158, will be rotated relatively to the head 127 as soon as the clutch members 168 and 166 are engaged, thereby operating the cams 149 to move the seaming rolls 63 to seaming position.

Mechanism for rocking the shaft 174 to bring about operation of the seaming mechanism is actuated in response to closing of the normally open switch 42 and consequently in response to movement of the can pad 52 to chucking position. The mechanism for rocking the shaft 174 includes a worm 176 rotatable in unison with the shaft 132 and meshing with a worm wheel 177 mounted to rotate freely on a shaft 178 journaled in a bracket 179. A predetermined period operation pilot clutch device includes a sleeve 180 secured to the shaft 178. The sleeve carries a pawl 181 urged by a spring 182 to move into the path of a lug 183 fast with a hub 184 secured to the worm wheel 177. Normally the pawl 181 is held out of the path of the lug 183 by a lever 185 fast with the clutch release shaft 35 previously referred to, the lever 185 being so mounted that in its normal position it bears against a heel 181^a on the pawl 181 so as to urge the nose of the pawl radially away from the lug 183. When the shaft 35 is rocked the lever 185 will swing so as to move out of engagement with the pawl heel 181^a thereby permitting the spring 182 to rock the pawl 181 and move its nose into the path of the lug 183. Thereupon the sleeve 180 and shaft 178 will be rotated in unison with the worm wheel 177.

Rotation of the sleeve 180 is utilized to rock the shaft 174 and effect engagement of the clutch elements 166 and 168 in the manner previously explained. Held fast to the sleeve 180 by screws 186 is a disc 187 formed with a notch 188. A pawl 189 fixed to a shaft 190 journaled on the bracket 179 has its nose 191 normally received in the notch 188. Also fixed to the shaft 190 is a lever 192. A link 193 is pivoted as at 194 to the lever 192 and is pivoted as at 195 to the interrupter arm 44 previously referred to.

In operation, when the can and can end have been chucked the solenoid 36 will be energized by closing of the switch 42. Operation of the solenoid 36 will rock the arm 38 and the clutch release shaft 35 to thereby swing the lever 185 away from the pawl heel 181^a. The pawl 181 will become engaged with the lug 183 so as to cause the sleeve 180 to be rotated. The disc 187 will rotate with the sleeve 180, causing the pawl nose 191 to be lifted out of the notch 188 onto the periphery of the disc 187, thereby rocking the shaft 190 and the lever 192 to lift the link 193, permit the normally closed switch 41 to open, and also to rock the shaft 174 and lever 173, thereby moving the clutch member 168 into engagement with the clutch member 166. The gears 158 and 157 will then be rotated differentially with respect to the

seaming head 127 so as to operate gears 156 and the cams 149 for moving the seaming rolls 63 to seaming position. Opening of the switch 41 in response to operation of the one-revolution clutch will de-energize the solenoid 36 so as to permit the lever 185 to be moved back into the path of the pawl heel 181^a but this will not interrupt driving engagement of the pilot clutch until the pawl 181 and sleeve 180 have made a complete revolution, whereupon the pawl heel 181^a will become engaged with the lever 185 so as to move the nose of the pawl 181 out of engagement with the lug 183, whereupon the sleeve 80 will come to rest.

The resetting arm 11 previously referred to is fixed to the shaft 178 and is equipped with a roller 196 engageable with the follower 12 projecting from the valve 2 for shifting the valve element 77 to relieve the vacuum in the chamber A after the seaming operation has been performed. The operation is so timed that valve member 77 is reset to relieve the vacuum in the chamber A before the sleeve 180 and disc 187 have performed a complete revolution. Hence, before the pawl nose 191 re-enters the notch 188 in the disc 187, the Syphon bellows 38 will expand and open the switch 32, thereby deenergizing the solenoid 28 and operating the valve 25 to move the piston 97 to the right, as viewed in Figure 14 and opening the switch 42. Thereafter, when the pawl nose 191 re-enters the notch 188, resultant closing of the switch 41 will not energize the solenoid 36, the circuit to which is broken by the open switch 42.

The pawl nose 191 will re-enter the slot 188 just as the nose of the pawl 181 is moved out of engagement with the lug 183, the drive clutch elements 167 and 169 will be disengaged to stop the seaming operation, and the parts will be brought to rest in their starting positions in readiness for performance of a new cycle.

A fly wheel 197 secured to the top of the shaft 132 may be turned manually for moving the parts slowly for adjusting or timing purposes.

A knock out pad 198 for forcibly ejecting or removing sealed containers from the chuck 62 is carried on the lower end of a stem 199 mounted to slide vertically in the cam member 143a. Pins 200 fast with the pad 198 extend through openings in the chuck 62 for preventing the pad 198 from rotating. The upper end of the stem 199 is bored to receive the reduced lower end of a vertically movable rod 201 mounted to slide within the sleeve 124.

The reduced upper end 202 of the rod 201 extends through a sleeve 203 threaded into the upper end of the sleeve 124. Nuts 204 threaded on the reduced upper end 202 of the rod 201 limit downward movement of the rod under the urge of a spring 205 interposed between the sleeve 203 and a shoulder 206 at the junction of the lower portion of the rod 201 and the reduced upper end portion 202 thereof.

In operation, when a can and end are chucked, the spring 205 will yield to permit the pad 198 to be raised by pressure exerted by the can end, the pad 198 then being received in a recess 207 in the bottom of the chuck 62. When the can supporting pad 52 is lowered the spring 205 will move the rod 201, stem 199 and pad 198 downwardly so as to eject the container forcibly from the chuck 62. With this arrangement the spring urged pad 198 will respond immediately to lowering of the pad 52, no other timing or actuating mechanism being required for operating the knock-out pad.

Preferably a mechanism cover 208 is removably mounted on top of the frame E.

The frame E includes a seaming mechanism housing 209 provided with an opening 210 facing towards the sealing chamber A. A plate 211 is arranged to close the opening but to be easily removable to afford access for servicing or adjusting the seaming mechanism. Normally the plate 211 is held in place by the bell or chamber A, as shown in Figure 2, gaskets being interposed between the plate and the housing 209 and bell A respectively.

To facilitate removal of the plate 211, the bell A is mounted to move vertically on the frame E so that it may be lowered, thereby making it possible to slide the plate out horizontally. In the illustrative embodiment the mechanism for moving the bell vertically includes a screw 212 secured to a lug 213 on the bell. The screw has threaded engagement with a captive nut 214 mounted to rotate in a frame carried bracket 215. The exterior of the nut 214 is formed as a worm wheel engaging a worm 216 carried by a shaft 217 rotatable in a frame mounted bearing 218. A hand wheel 219 is provided for rotating the shaft 217 and thus raising or lowering the bell A.

Features shown and described in the above specification but not claimed have been claimed in copending divisional applications filed October 4, 1946, Ser. No. 701,184, and October 9, 1946, Ser. No. 702,334, to which reference is made here.

The machine disclosed herein embodies the invention in the form now preferred but it will be understood that changes may be made without departing from the invention as defined in the claims.

We claim:

1. In a container sealing machine, a sealing chamber having an access opening; a door for said opening; seaming mechanism in said chamber including a chuck element and a container supporting element; means for drawing a vacuum in said chamber; means for moving one of said elements relatively toward the other of said elements to place a container carried on said supporting element in vacuumizing position close to but spaced from said chuck; means for stopping said one of said elements when said container has been placed in said vacuumizing position; and fluid pressure operated means actuated by a predetermined degree of vacuum in said chamber for moving one of said elements to place said container in chucked position.

2. In a container sealing machine, a sealing chamber having an access opening; a door for said opening; seaming mechanism in said chamber including a chuck element and a container supporting element; means for drawing a vacuum in said chamber; fluid pressure operated means for moving one of said elements relatively toward the other of said elements to place a container carried on said supporting element in vacuumizing position close to but spaced from said chuck; and other fluid pressure operated means actuated by a predetermined degree of vacuum in said chamber for moving one of said elements to place said container in chucked position.

3. In a container sealing machine, a sealing chamber having an access opening; a door for said opening; seaming mechanism in said chamber including a chuck element and a container supporting element; means for drawing a vacuum in said chamber; means for moving one of said elements relatively toward the other of said elements to place a container carried on said sup-

porting element in vacuumizing position close to but spaced from said chuck; fluid pressure operated means for moving one of said elements to place a container carried by said supporting element in chucked position; a normally closed valve for actuating said fluid pressure operated means; circuit means including a solenoid for opening said valve; circuit means including a switch in circuit with said solenoid; and a device responsive to attainment of a predetermined vacuum condition in said chamber for closing said switch.

4. In a container sealing machine, a sealing chamber having an access opening; a door for said opening; seaming mechanism in said chamber including a chuck element and a container supporting element; means for drawing a vacuum in said chamber; fluid pressure operated means for moving one of said elements relatively toward the other of said elements to place a container carried on said supporting element in vacuumizing position close to but spaced from said chuck; other fluid pressure operated means actuated by a predetermined degree of vacuum in said chamber; and means connecting said two fluid pressure operated means for supplementing the operative effort of said other fluid pressure operated means to the operative effort of said first-named fluid pressure operated means to move said one of said elements further and thereby to place said container in chucked position.

5. In a container seaming machine, seaming mechanism including a chuck element; a container supporting element; means for moving said supporting element to place a container carried thereon in chucked position; means controlling operation of the seaming mechanism; circuit means including a solenoid for actuating said control means to operate said seaming mechanism; and a switch in said circuit with said solenoid and being operable in response to the movement of said supporting element which places said container in chucked position.

6. In a container seaming machine, seaming mechanism including a chuck element; a container supporting element; means for moving said supporting element to place a container carried thereon in chucked position; driving means; means including a normally disengaged predetermined period operation clutch for effecting operation of said seaming mechanism by said driving means; circuit means including a solenoid operative to effect engagement of said clutch; a normally open switch; means connecting said switch in circuit with said solenoid, said switch being operable to closed position in response to movement of said supporting element and said container to chucking position; a normally closed switch; means connecting said normally closed switch in circuit with said solenoid; and means for opening said normally closed switch in response to engagement of said clutch.

7. In a container sealing machine, a sealing chamber having an access opening; a door for said opening; means for vacuumizing said chamber in response to closing of said door; seaming mechanism including a chuck element and a container supporting element in said chamber; means responsive to closing of said door for moving one of said elements toward the other of said elements but only part way to chucking position; and fluid pressure actuated means responsive to vacuumizing of the chamber for effecting movement of said one of said elements to chucking position.

8. In a container sealing machine, a sealing chamber having an access opening; a door for said opening; means for vacuumizing said chamber in response to closing of said door; seaming mechanism including a chuck element and a container supporting element in said chamber; means responsive to closing of said door for moving one of said elements toward the other of said elements but only part way to chucking position; fluid pressure actuated means responsive to vacuumizing of the chamber for effecting movement of said one of said elements to chucking position; and means responsive to movement of said one of said elements to chucking position for starting operation of said seaming mechanism.

9. In a container sealing machine, a sealing chamber having an access opening; a door for said opening; means for vacuumizing said chamber in response to closing of said door; seaming mechanism including a chuck element and a container supporting element in said chamber; means responsive to closing of said door for moving one of said elements toward the other of said elements but only part way to chucking position; fluid pressure actuated means responsive to vacuumizing of the chamber for effecting movement of said one of said elements to chucking position; means responsive to movement of said one of said elements to chucking position for starting operation of said seaming mechanism; and means for devacuumizing said chamber and stopping the seaming mechanism after a predetermined period of operation thereof.

10. In a container sealing machine, a sealing chamber; means for drawing a vacuum in said chamber; seaming mechanism including a chuck element and a container supporting element in said chamber; a reciprocatory member mounting one of said elements to move relatively toward the other of said elements; a first piston and cylinder motor drivingly connected to said member for moving said one of said elements toward said other of said elements; means including a stop for arresting movement of said member before a supported container has been chucked; and a second piston and cylinder motor actuated by a predetermined degree of vacuum in said chamber for displacing said stop to enable further movement of said member and said one of said elements to chucking position.

11. In a container sealing machine, a sealing chamber; means for drawing a vacuum in said chamber; seaming mechanism including a chuck element and a container supporting element in said chamber; a reciprocatory member mounting one of said elements to move relatively toward the other of said elements; a piston and cylinder motor drivingly connected to said member for moving said one of said elements toward said other of said elements; a cam follower connected to said member; a cam normally interposed in the path of said follower for arresting movement of said member and said one of said elements before a supported container has been chucked; and means actuated by a predetermined degree of vacuum of said chamber for moving said cam to cause it to positively drive said follower and with it said member and said one of said elements to move a supported container to chucked position.

12. In a container sealing machine, a sealing chamber; means for drawing a vacuum in said chamber; seaming mechanism including a chuck element and a container supporting element in said chamber; a reciprocatory member mounting one of said elements to move relatively toward the other of said elements; a first piston and cylinder motor drivingly connected to said member for moving said one of said elements toward said other of said elements; a cam follower connected to said member; a cam normally interposed in the path of said follower for arresting movement of said member and said one of said elements before a supported container has been chucked; and a second piston and cylinder motor actuated by a predetermined degree of vacuum in said chamber for moving said cam to cause it to positively drive said follower and with it said member and said one of said elements to move a supported container to chucked position.

13. In a container sealing machine, a sealing chamber; means for drawing a vacuum in said chamber; seaming mechanism including a chuck element and a container supporting element in said chamber; a reciprocatory member mounting one of said elements to move relatively toward the other of said elements; means connected to said member for moving said one of said elements toward said other of said elements; a cam lever formed with a cam slot; means pivoting said cam lever with opposed faces of the cam slot spaced from each other in the direction of movement of said member; a cam follower on said member and extending into said cam slot, one of said cam slot surfaces constituting a stop engageable by said follower for arresting movement of said member before a supported container has been chucked, and the other of said cam slot surfaces constituting a follower driving surface; and means actuated by a predetermined degree of vacuum in said chamber for rocking said cam lever to bring said follower driving surface into engagement with said follower for driving the latter and moving said member and said one of said elements to chucking position.

ALFRED L. KRONQUEST.
